[57] CLAIM

The ornamental design for a flip-top display for wall and floor covering samples, as shown and described.

DESCRIPTION

FIG. 1 is a perspective view of the flip-top display for wall and floor covering samples with the flip-top closed;
FIG. 2 is a reduced perspective view thereof with the flip-top open;

FIG. 3 is an enlarged right side view thereof, left side view being a mirror image thereof;
FIG. 4 is an enlarged front view thereof;
FIG. 5 is an enlarged back view thereof;
FIG. 6 is a reduced top view thereof; and,
FIG. 7 is a reduced bottom view thereof.

The broken line showing of a hand is for illustrative purposes only and forms no part of the claimed design.
